(57) **CLAIM**

The ornamental design for a mattress or mattress topper, as shown and described.

DESCRIPTION

FIG. 1 is a right side elevational view of a mattress or mattress topper showing my new design;

FIG. 2 is a top plan view of the mattress or mattress topper of FIG. 1;

FIG. 3 is a rear elevational view of the mattress or mattress topper of FIG. 1;

FIG. 4 is a front elevational view of the mattress or mattress topper of FIG. 1;

FIG. 5 is a bottom plan view of the mattress or mattress topper of FIG. 1; and

FIG. 6 is a left side elevational view of the mattress or mattress topper of FIG. 1; and,

FIG. 7 is an enlarged fragmental perspective view of the left front corner of the mattress or mattress topper illustrating the three dimensional depth of the design.
